UNITED STATES PATENT OFFICE

2,544,016

FIRE EXTINGUISHING SYSTEM

Charles A. Getz, Glen Ellyn, Ill., assignor, by
mesne assignments, to Cardox Corporation,
Chicago, Ill., a corporation of Illinois

Application September 28, 1942, Serial No. 459,994

9 Claims. (Cl. 169—11)

1

This invention relates to new and useful improvements in fire extinguishing systems employing carbon dioxide as the extinguishing medium.

The fire extinguishing method disclosed and claimed in the patent to Eric Geertz, numbered 2,143,311, and issued January 10, 1939, deals with confining any desired quantity of liquid carbon dioxide in an insulated storage tank and maintaining the liquid at any preselected subatmospheric temperature, and its corresponding low vapor pressure until used.

Prior to the development of this patented method, liquid carbon dioxide employed in fire extinguishing systems was always confined in one or more relatively small, uninsulated cylinders. As the cylinders were directly exposed to the surrounding atmosphere, the temperature of the carbon dioxide stored therein varied considerably and the pressure was usually well over one thousand pounds per square inch. Conventional carbon dioxide cylinders used in fire extinguishing systems were capable of storing from fifty to seventy pounds of liquid which required a bank of from forty to thirty cylinders for each ton of extinguisher capacity.

Because of the high pressures at which the carbon dioxide was stored in such prior commercial systems, the only practical means that was ever developed for controlling the release of the medium consisted of a sealing disc for each cylinder and a reciprocating cutter that had to be forcibly propelled to cause it to puncture the disc. The disc cutter of at least one cylinder of each bank had to be operated by some external source of power, such as a dropped weight, an exploded powder charge, or a manually delivered blow. In some systems the carbon dioxide released from one or more cylinders of a bank was employed as the source of power for operating the cutters of the remaining cylinders. It will be appreciated, however, that regardless of the source of power employed and the mechanism utilized to reciprocate the cutters by means of such power, each fifty to seventy pounds of carbon dioxide delivered to the pipe lines of a fire extinguishing system required the operation of a separate release mechanism.

The use of low, uniform pressure liquid carbon dioxide from a single storage tank in fire protection systems has now made it possible to employ a single valve for effecting complete control of the release of all, or any portion of the carbon dioxide from the storage tank. This single, or master, control valve may be either opened

2

or closed as a result of direct manual control or its opening and closing may be accomplished as a result of automatic detection of a fire by means of thermo-responsive devices, or the like.

5 When two or more hazards are to be separately protected by a single system, the ability to employ a master valve to control the release of the carbon dioxide from the storage tank into the header, or distribution manifold, of the piping and 10 supplemental selector valves to control the delivery of the carbon dioxide from the header to the individual hazards makes it possible to provide a non-pressure header; i. e., a header that is not filled with and subject to the pressure of the extinguishing medium except when the system is being operated to extinguish a fire. Because of that fact, the various selector valves normally are not relied upon to confine the carbon dioxide in the storage tank. The master 15 control valve, therefore, is the only one which must be maintained "bubble-tight"; i. e., capable of preventing leakage of the carbon dioxide.

The use of valves for effecting release of the carbon dioxide into the pipe line header and for 20 effecting flow from the header through one or more branch pipe lines makes it possible to employ electric circuits and their devices for detecting fires and controlling the opening and closing of said valves.

25 It is the primary object of this invention to provide a fire extinguishing system which employs as the extinguishing medium carbon dioxide confined at a controlled temperature and pressure in an insulated storage tank, and which 30 employs valves for completely controlling the delivery of the carbon dioxide to the one or more hazards protected by the system.

35 A further important object of the invention is to provide a system of the aforementioned type 40 in which electric circuits and devices are normally employed for detecting fire at one or more hazards and for automatically effecting opening of a master control valve and the proper selector valve or valves associated with the 45 threatened hazard or hazards.

Another object of the invention is to provide such an automatic, electrically controlled system with means which will permit both the master and the selector valves to be manually controlled 50 without in any way disturbing the electric control mechanism.

A still further principal object of the invention is to provide means for automatically placing the system under full manual control in case of 55 failure of electric power.

Other objects and advantages of the invention will be apparent during the course of the following description.

In the accompanying drawings forming a part of this specification and in which like numerals are employed to designate like parts throughout the same,

Figure 1 is a diagrammatic view of the fire extinguishing system embodying this invention.

Figure 2 is a vertical sectional view of the master control valve which is normally employed for maintaining the carbon dioxide confined in its storage tank whereby the distribution header will be of the non-pressure type.

Figure 3 is a vertical sectional view of the type of selector valve employed for controlling the flow of the extinguishing medium from the header to a hazard threatened by fire.

Figure 4 is a partly elevational view and partly vertical sectional view of a form of pilot valve which will function to automatically effect opening of the master control valve and conversion of the non-pressure header to a pressure header upon failure of the electric power.

Figure 5 is a vertical sectional view taken on line 5—5 of Fig. 4, and

Figures 6 and 7 are detail perspective views of elements incorporated in the electric control mechanism of Figs. 4 and 5.

In the drawings, wherein for the purpose of illustration is shown the preferred embodiment of this invention, and first particularly referring to Fig. 1, the reference characters A and B designate two different fire hazards which are to be given fire protection by the extinguishing system embodying this invention. These hazards are specifically illustrated as being enclosed spaces but it is to be understood that the system is not limited in its use to the protection of this type of hazard. By employing different types or sizes and different arrangements of discharge devices, any kinds of hazards may be protected by this extinguishing system. The hazards A and B are illustrated as being of different sizes. This type of illustration is intended to show that the system is of such a flexible character that it can be employed for efficiently extinguishing fires or for protecting hazards which require different amounts of the extinguishing medium.

The proper amount of liquid carbon dioxide to afford the desired protection for the hazards A and B is maintained in the insulated storage tank 10. This liquid carbon dioxide is maintained at a desired subatmospheric temperature, and its corresponding vapor pressure, in accordance with the teachings of the aforementioned patent issued to Eric Geertz. The amount of liquid carbon dioxide stored in the tank 10 may be sufficient for providing the following types of discharges:

1. A single discharge that will effect extinguishment of a fire in only one of the two hazards A and B.

2. A single discharge for each one of the two hazards A and B with no reserve for extinguishing a fire in either hazard in case of a reflash.

3. A two "shot" discharge for one of the two hazards which will effect extinguishment of a fire and provide additional protection in case of a reflash.

4. A two "shot" discharge for each one of the two hazards.

Of course, the size of the storage tank 10 will determine the quantity of liquid carbon dioxide that is provided for protecting the hazards. The

larger the size of the storage tank 10, the higher the initial cost of the system. The character of the various hazards to be protected, their location with respect to each other, and other factors which will be apparent to persons skilled in the art will govern the amount of liquid carbon dioxide which must be maintained in storage to provide adequate protection for the hazards.

A dip-tube or pipe 11 extends into the storage tank 10 for providing the discharge pipe line 12 with liquid carbon dioxide. This pipe line has connected therein a manually operable shut-off valve 13 which normally is open. This valve is only closed when it becomes necessary to make repairs to or alterations in the downstream pipe lines and/or their valves, etc.

Beyond the shut-off valve 13 the discharge pipe line 12 is connected to the master control valve 14 which is normally relied upon to keep the carbon dioxide confined in the storage tank 10 and to keep pressure off of the header, or distribution piping 15 which connects the master control valve 14 with the selector valves 16. These selector valves function, after opening of the master control valve 14, to deliver the carbon dioxide to the proper hazard or hazards through the branch lines 17 and their discharge devices 18.

When the detail features of construction of the master control valve 14 and the selector valves 16 are described in connection with the disclosures of Figs. 2 and 3, it will be seen that these valves are of the solenoid controlled type. The master control valve 14 is provided with a solenoid control unit 14a. The selector valves 16 are each provided with a solenoid control unit 16a. It will be seen that the solenoid control units 14a and 16a are of identical construction and are susceptible of interchangeable attachment to the master control valve 14 and the selector valves 16. The master control valve solenoid unit 14a is provided with electric wires 19 which connect the coil of this solenoid with suitable circuit making, breaking and holding relays, of conventional design and operation, located in the electric control box 20. Wires 21 and 22 connect the solenoid control units 16a of the two selector valves 16 with proper relay devices in the control box 20. No attempt has been made to illustrate the specific relay devices which are confined within the box 20 because suitable units are readily available on the open market and any skilled electrician should be able to select the proper types and sizes of circuit controls and interconnect them in a proper manner to accomplish the results which will be set forth as the description of this system proceeds.

Power supply lines 23 extend from a suitable source of supply to the terminals 24 of the double-pull, single-throw switch 25. When this switch is closed, current will be supplied the various instrumentalities in the box 20 through the wires 26.

Each one of the two hazards A and B is provided with a suitable number of circuit closing, fire detecting devices 27. The fire detecting devices 27 for each hazard are connected in parallel with the circuit wires 28 which extend to the electric control box 20. Each one of these fire detecting devices 27 will be capable of functioning to close the circuit between its respective wires 28 when said device 27 is subjected to a certain degree of temperature, or a certain rate-of-rise of temperature as a result of a fire in the hazard protected by the detecting device 27.

5 Each one of the fire detecting circuits, formed by the wires 28, may be closed by a manual switch that is diagrammatically illustrated at 29. It will be appreciated, therefore, that the extinguishment of a fire in either of the two hazards A and B may be accomplished without actuation of any one of the automatic heat detecting devices 27 in case a person discovers a fire before the temperature created by the fire has risen to a value which will actuate a detector 27.

To briefly describe the operation of the portion of the fire extinguishing system so far referred to, it will be explained that should a fire be detected either manually or automatically in either one of the hazards A and B, the proper detection circuit 28 will be closed for that hazard. The closing of that particular detector circuit will bring about operation of the instrumentalities in the box 20 to close the circuit to the solenoid control unit 14a of the master control valve 14 through its circuit wires 19. A circuit will also be established to the solenoid control unit 16a of the selector valve 16 that is operatively associated with the hazard that is threatened by the fire. This selector valve circuit will be closed either through the wires 21 or the wires 22. The closing of these solenoid circuits will bring about opening operations of the master control valve 14 and the particular selector valve 16. The liquid carbon dioxide then will flow from the storage tank 10 through the delivery pipe line 12 to the master control valve 14 and through this valve into the header 15. Although the entire header will be filled with the carbon dioxide, discharge from the same will only occur through the selector valve 16 that has had its solenoid control unit energized to effect opening of the valve. Flow of the carbon dioxide will continue through the opened selector valve 16 into the branch pipe line 17 and from this pipe line to the hazard through the discharge device 18.

By employing a "Time Cycle Controller" of the type disclosed in the Joseph H. Staley Patent, numbered 2,141,024 in the electric control box 20 for closing and opening the circuits to the solenoid control units of the master control valve 14 and the proper selector valve 16, these valves may be held open for only a certain length of time and then automatically closed. By employing this type of timed control, it will be appreciated that a fire can be extinguished in either of the two hazards without exhausting all of the carbon dioxide stored in the tank 10. It further will be noted that the discharge devices 18 for the two hazards A and B are of different sizes, a smaller discharge device being employed for the smaller hazard B. As the rate of discharge of the carbon dioxide into a hazard will depend on the size of the discharge device 18 associated with that hazard, the amount of carbon dioxide discharged into a hazard for a given length of time can be controlled by the size of the discharge device. The size of a selector valve 16 and its branch pipe 17 also can be employed for controlling the rate of discharge of the carbon dioxide to a hazard.

When the detail features of construction of the master control valve 14 are fully described in connection with the disclosure of Fig. 2, it will further be understood that this valve is opened as a result of the creation of a differential fluid pressure condition within the valve housing. This valve opening, differential fluid pressure condition is created by the admission of fluid pressure

6 to the portion 14b of the master control valve housing.

Fluid pressure can be delivered to the valve housing portion 14b from the delivery pipe line 12 through the coupling 30 and either the branch line 31 or the branch line 32. The branch line 31 is controlled by a manual valve 33 so that the master control valve 14 can be caused to open by manual operation of the valve 33. The flow of fluid pressure through the branch line 32 into the master control valve housing portion 14b is controlled by the valve 34. This valve is normally held closed by the electrical device 35 which is normally energized by the flow of current through the circuit wires 36. This electrical control device 35 is illustrated in detail in Figs. 4 to 7 inclusive and will be fully described at a later point. It will be explained at this time, however, that whenever there occurs a failure of power the electric control device 35 will become deenergized so that it will no longer hold the valve 34 closed. This valve will then open and deliver fluid pressure to the housing portion 14b of the master control valve 14. This master control valve then will be opened long enough to change the normally non-pressure header 15 to a pressure header; i. e., the carbon dioxide will fill the header 15 up to the selector valves 16. After the pressure in the header 15 is equalized with the pressure in the delivery pipe line 12, the master control valve 14 will close. The pressure in the header will be maintained equalized with the pressure in the delivery pipe line 12 as long as the valve 34 stays open. Any subsequent rapid drop in pressure that occurs in the header, such as would take place if a selector valve were opened, will cause the master control valve to open automatically so that carbon dioxide will be delivered to the hazard associated with the opened selector valve. This manual operation of a selector valve can be accomplished by the attachment 16b. This manual operating mechanism for a selector valve will be described in detail in connection with the disclosure of Fig. 3.

The master control valve 14 will remain closed after the branch line valve 34 is closed. Therefore, by discharging the carbon dioxide in the header 15 by opening one of the selector valves 16, the system may be returned to its normal condition; that is, with the header 15 in a non-pressure condition.

Of course, if the valve 34 is opened as a result of deenergizing of the electric device 35 by failure of the electric power and the master valve 14 is operated to convert the non-pressure header 15 into a pressure header, the selector valves 16 will automatically function in response to detection of a fire in a hazard if the power supply comes back on and the electric device 35 is not immediately reset. In other words, the selector valves 16 are capable of responding to automatic detection of a fire by the detecting devices 27 regardless of whether the master valve 14 is opened as a result of energization of its solenoid control unit 14a, through the operation of the detecting device 27, or is opened as a result of the pressure drop that is caused by the opening of the selector valve.

70 A fire may occur at a time when either one or both of the electric detecting circuits for the hazards are out of commission. The system then can be entirely manually operated. The master valve 14 can be opened by opening the manual valve 33 and either or both of the selector valves

16 may be opened by their manual operating devices 16b.

It will be noted by inspecting Fig. 1 that the branch pipe line 31 is provided with a check valve 37 while the short length of pipe 38 which is common to both of the branch lines 31 and 32 is provided with a check valve 39. The functions performed by these check valves 37 and 39 will be explained in connection with the detailed descriptions of the master valve 14 and the electric device 35.

The master control valve 14 now will be described in detail in connection with the disclosure of Fig. 2. The delivery pipe line 12 is suitably connected to the inlet side 40 of the valve body or casing 41. The header or distributing pipe 15 is suitably connected to the outlet side 42 of the valve casing 41. A partition 43 separates the inlet and outlet sides 40 and 42 of the valve casing. This partition is provided with an opening or aperture 44 in which is threadedly mounted a seat 45. This type of valve construction inherently functions to cause the pressure of the fluid flowing through the partition opening to drop so that the pressure of the fluid flowing in the outlet 42 will be substantially less than the pressure of the fluid flowing in the inlet 40. A valve 46 is adapted to engage the seat 45, through the medium of its seating ring 47, to prevent the flow of the carbon dioxide through the partition opening 44. The valve 46 is guided in its seating and unseating movements by means of a plunger 48 that is movable in the cylinder 49. A valve loading spring 50 normally functions to urge the valve 46 toward the seat 45. It will be appreciated that the pressure of the carbon dioxide in the inlet side 40 of the valve casing 41, also, will normally function to hold seated the valve 46.

The valve casing 41 has suitably connected thereto the fluid pressure casing 14b which was referred to in connection with the description of the disclosure of Fig. 1. This pressure casing portion is provided with a cylinder 50' in which is reciprocally mounted the fluid pressure piston 51. A piston rod 52 forms a part of the piston 51 and is connected at its lower end to the valve rod or stem 53. The piston rod 52 is provided with a bore 54 that communicates with the pressure chamber 55 that is formed between the upper end of the piston 51 and the closed end 56 of the pressure casing 14b. The valve rod 53 also is provided with a bore 57 which communicates with the bore 54 of the piston rod and is provided with lateral ports 58 that provide communication between the outlet side 42 of the partition 43 and the valve rod bore 57. A plug 59 is threaded in the upper end of the piston rod bore 54 and is provided with a relatively small port or aperture 60. This port or aperture 60 is of proper diameter to control the rate of flow of fluid from the pressure chamber 55 into the bores 54 and 57 and through the ports 58 into the outlet side 42 of the valve casing 41.

A by-pass duct 61 is formed in the walls of the valve casing 41 and the fluid pressure casing 14b for providing a flow path between the inlet side 40 of the valve casing 41 and a chamber 62 that is formed between the closed end 56 of the pressure casing 14b and the base or boss 63 of the solenoid control unit 14a. The closed end 56 of the fluid pressure casing 14b is provided with an opening 64 in which is mounted an apertured plug 65. The aperture of this plug is of greater diameter than the aperture 60 of the

7
8
plug 59 so that fluid pressure can be admitted to the pressure chamber 55, by way of the by-pass 61 and the chamber 62, at a more rapid rate than it can flow out of the pressure chamber 55 through the bores 54 and 57 of the piston stem 52 and valve stem 53.

A pilot valve 66 is adapted to cooperate with the upper end of the apertured plug 65 for opening and closing the aperture through the plug to control the flow of carbon dioxide from the chamber 62 into the pressure chamber 55. This pilot valve 66 is operated by the armature 67 of the solenoid coil 68. It will be seen by inspecting Fig. 2 that the solenoid coil 68 is detachably threadedly connected at 68a to the base or boss 63. When this solenoid coil is energized through the wires 19 the armature 67 will be raised for unseating the pilot valve 66. When the coil 68 is de-energized, the armature 67 will seat the pilot valve 66. It will be appreciated, therefore, that when the solenoid coil 68 is energized to unseat the pilot valve 66, carbon dioxide will be permitted to flow through the by-pass 61 into the chamber 62 and through the aperture of the plug 65 into the pressure chamber 55. As the diameter of this chamber, and the piston 51, is greater than the diameter of the valve 46, the carbon dioxide pressure built up in the pressure chamber 55 will cause the valve to be unseated against the fluid pressure applied to the valve and the force of the valve loading spring 50. After the valve 46 is unseated by the fluid pressure developed in the pressure chamber 55, it will be held open until the supply of fluid pressure to chamber 55 is stopped. This is due to the fact that the pressure of the fluid on the outlet side 42 of the valve partition 43, which pressure is acting on the lower face of the power piston 51, is substantially less than the pressure developed in the pressure chamber 55, which pressure is acting on the upper face of the power piston 51. This difference in the fluid pressures in the outlet 42 and the chamber 55 is sufficient to overpower the spring 50. When the solenoid coil 68 is de-energized, the pilot valve 66 will be seated and flow of carbon dioxide from the valve casing inlet 40 into the pressure chamber 55 will cease. The carbon dioxide pressure built up in the chamber 55 will then bleed off through the aperture opening 60 of the plug 59 into the bores 54 and 57 of the piston rod 52 and valve rod 53. This pressure will be dissipated in the outlet side of the valve casing 41. After the pressure has dropped sufficiently in the chamber 55, the valve 46 will be seated by the spring 50 and the carbon dioxide pressure in the inlet side 40 of the valve casing 41. Of course, opening of the valve 46 will permit the carbon dioxide to flow into the outlet side 42 of the valve casing 41 and into the header 15.

Referring now to Figs. 1 and 2, it will be seen that the delivery pipe 12 has a short length of pipe 69 coupled thereto and this pipe is connected to one branch of the coupling 70. This coupling 70 connects the short pipe 69 to the two branch lines 31 and 32. Carbon dioxide pressure, therefore, will constantly be applied to both of the branch lines.

The branch line 31 has connected therein an ordinary manual valve 33 which is capable of being opened and closed. This manual valve 33 will control the flow of carbon dioxide through the branch line 31 to the check valve 37. This check valve is connected to the coupling 71 by the nipple 72. The short pipe section, with its

check valve 39, is connected to a second branch of the coupling 71 while the branch line 32 is connected to the third branch of the coupling 71. The short pipe section 38 is tapped into the opening 73 that directly communicates with the pressure chamber 55 formed in the pressure casting 14b.

It will be appreciated, therefore, that when the manual pilot valve 33 is opened carbon dioxide will flow from the delivery pipe 12 through the branch line 31 and through both of the check valves 37 and 39 into the pressure chamber 55. Pressure will develop in this latter chamber and the valve 46 will be unseated. When the manual pilot valve 33 is again closed, the pressure built up in the chamber 55 will be dissipated through the bores 54 and 57 and the valve 46 will again be seated to stop the flow of carbon dioxide through the valve casing 41 from the delivery pipe 12 to the header 15.

When the electrically controlled pilot valve 34 is opened, carbon dioxide will flow through the branch line 32 into the coupling 71 and through the short pipe section 38, and its check valve 39, into the pressure chamber 55 for building up pressure in this latter chamber to unseat the valve. It will be appreciated that the check valve 37 will function to prevent carbon dioxide from flowing from the branch line 32 into the branch line 31 up to the discharge side of the manual pilot valve 33. The check valve 31, therefore, functions to reduce the volume or pipe capacity that must be filled with carbon dioxide when the branch line 32 is opened by opening of the pilot valve 34. When the pilot valve 34 is again closed, the carbon dioxide pressure will be bled from the chamber 55, and the branch line 32 downstream of the closed valve 34, and the valve 46 will be permitted to close.

The check valve 39 functions to reduce the volume or pipe capacity that must be filled with carbon dioxide when the solenoid operated pilot valve 66 is unseated. That is to say, when the carbon dioxide is permitted to flow through the by-pass 61, the chamber 62 and the aperture of the plug 65 into the pressure chamber 55, the flow of carbon dioxide into the branch lines 31 and 32 will be prevented by the check valve 39.

The electrically controlled pilot valve 34 and its control mechanism 35 will be described in detail in connection with the disclosures of Figs. 4 to 7 inclusive.

The pilot valve 34 includes a main body portion 74 which is hollowed out at 75 to form a chamber. One end of this chamber is closed by the cap 76 that is formed with a valve seat 77 at the inner end of its bore 78. The two portions of the branch line 32 are coupled to the openings 79 and 80 of the main valve body 74 and the cap 76 respectively. A valve 81 is positioned within the chamber 75. This valve is adapted to engage the seat 77 to cut off communication between the two portions of the branch line 32. A spring 82 normally tends to move the valve 81 away from the seat 77. A valve stem 83 is connected at its inner end to the valve 81 and extends out of the chamber 75 and into the interior of the box 84 of the electric control device 35.

The end of the valve stem 83 which is located in the box 84 is engaged by an end of the adjustable set screw 85. This set screw is carried by the main valve operating lever 86 which is shown in detail in Fig. 6. It will be seen that this main lever is provided with a threaded aper-

ture 87 to receive the set screw 85. One end of the lever is provided with an aperture 88 and a concentric recess or socket 89. The remaining end portion of the lever is cut away at 91 to form the two shoulders 92.

A cap screw 93 is secured to the bottom wall of the box 84 and passes through the aperture 89 of the lever 86 with enough clearance to permit the lever to rock or pivot relative to the screw. A spring 94 is positioned over the cap screw 93 so as to have its lower end seated in the recess or socket 89 formed in the main lever 86. An adjustable nut 95 is threaded on the free end of the cap screw 93 for adjusting the force developed by the spring 94. A stop 96 cooperates with the spring loaded end of the lever 86 to limit movement of the lever.

The shoulders 92 of the main lever 86 are adapted to be engaged by the fingers 97 of the trip levers 98. These two trip levers are arranged in parallelism and are pivotally connected at their lower ends 99 to the mounting block 100 by means of the pin 101. The upper ends of these trip levers are notched at 102 for receiving the transverse pin 103 that is carried by the projecting end of the solenoid armature 104. This armature forms a part of the solenoid 105 that is supplied with current through the circuit wires 36.

Fig. 1 discloses these circuit wires as extending from the main supply wires 26. It will be appreciated, therefore, that as long as current is supplied to the electric control box 20, current will flow through the wires 36 for energizing the solenoid coil 105. When the solenoid coil is energized, its armature 104 will be held in the position illustrated in Fig. 4. This position of the armature will hold the trip levers 98 in their proper positions for engaging the shoulders 92 of the main valve control lever 86. Therefore, the energized solenoid 105 and its trip levers 98 will hold down one end of the main valve lever 86 while the other end is being held down by the spring 94. The lever 86, when held in the position illustrated in Figs. 4 and 5, will function to hold the pilot valve member 81 in engagement with its seat 77 against the pressure of the carbon dioxide in the bore 78 of the cap 76. When the solenoid coil 105 is de-energized, by interruption of the flow of current through the main supply wires 26 and circuit wires 36, the solenoid armature 104 will be permitted to move to the left, as viewed in Fig. 4. This outward movement of the solenoid armature 104 will cause the trip levers 98 to swing about their pivot pin 101 for moving their fingers 97 out of engagement with the shoulders 92 of the valve control lever 86. Release of this lever 86 at one end will permit the pressure of the carbon dioxide in the cap bore 78 and the spring 82 to move the pilot valve body 81 away from its seat 77. Carbon dioxide will then flow through the branch line 32 into the pressure chamber of the master control valve 14 for opening that valve.

The solenoid operated trip mechanism will not automatically reset itself when current flow is again provided in the circuit wires 36. To manually reset this trip mechanism, the cover plate 106 must be removed from one end of the box 84. An opening 107 is provided in the end of the box to permit access to be had to the lever 86 and the trip levers 98 for resetting the same in the positions illustrated in Figs. 4 and 5.

One of the selector valves 16 is illustrated in detail in Fig. 3. By comparing this selector valve showing with the showing of the master control

valve 14 in Fig. 2, it will be seen that the selector valve differs from the master control valve only by not having the tapped opening 13 that communicates with the pressure chamber 55 and by having the manual operating mechanism 16b added thereto. Therefore, all of the elements which are common to the two valves will be identified by the same reference characters and a detailed description of these elements will not be given in connection with the selector valves.

The means for manually opening the valve 48 against the pressure of its spring 56 and the pressure of the carbon dioxide in the inlet portion 40 of the valve casing 41 now will be described. The guiding piston or plunger 108 for the valve 48 is of tubular formation. The lower end of this piston or plunger bore has threaded therein the plug 109 which is suitably connected to the stem 110. This stem extends through an internally screw threaded opening 111 formed in the valve 48 casing cap 112 and is provided with a threaded portion 113 that engages the threads of the opening 111. The valve stem extends through a packing gland 114 to provide the projecting portion 115. The extremity of this portion is squared at 116 for engagement by a suitable socket wrench.

The valve casing cap 112 has the projection 117 externally screw threaded for having the combined closure and socket wrench member 118 threaded connected thereto. It will be noted that this member 118 is hollowed out at 119 to accommodate the projecting portion 115 and squared portion 116 of the valve stem 110. A packing gasket 120 is provided to prevent leakage past the screw threaded connection between the valve casing cap extension 117 and the member 118. It will be appreciated, therefore, that when the member 118 is arranged as shown in Fig. 3 it will function to prevent any possible leakage from the valve casing 41 along the valve stem 110.

The socket wrench portion of the member 118 consists of the element 121 which is held in place by the pin 122. An operating wheel 123 is suitably attached to the member 118.

When it becomes desirable to open the selector valve manually, the combined closure and socket wrench member 118 is detached from the cap extension 117 by manipulation of the wheel 123 to unscrew the member 118 from the extension 117. After the member 118 is detached from the cap extension 117, the member can be turned end for end to engage the socket wrench element 121 with the squared end 116 of the valve stem 110. The valve stem can be rotated by this member 118 for causing the threaded portion of the valve stem to move along the threaded bore 111 of the cap 112. This outward movement of the valve stem 110 will pull the valve 48 away from its seat 45. This movement of the valve 48 away from its seat will not be accompanied by movement of the valve rod 53 and the piston 51 because of the loose telescopic joint 124.

It will be noted that the master control 14 is adapted for manual control through the medium of the branch line 31 and the manual pilot valve 33 while the selector valves are adapted for manual control through the medium of the manually operable socket wrench attachment 16b. It will be appreciated, however, that both the master control valve and the selector valves may be of the same construction so that they can all be manually controlled by either the branch line and pilot valve structure or by the socket wrench structure, as desired.

It is to be understood that the form of this invention herewith shown and described is to be taken as the preferred example of the same, and that various changes in the shape, size, and arrangement of parts may be resorted to without departing from the spirit of the invention or the scope of the subjoined claims.

Having thus described the invention, I claim:

1. A fire extinguishing system for protecting a plurality of separate hazards, comprising a storage tank for supplying liquid carbon dioxide to the system, a delivery pipe extending from the tank, a master valve for controlling the flow of carbon dioxide through the delivery pipe, a header connected to the outlet of the master valve, a separate branch pipe line extending to each hazard from the header, a selector valve for controlling each branch pipe line, electrical means for effecting opening operation of the master valve and one selector valve for effecting delivery of the carbon dioxide to the hazard associated with the opened selector valve, and means operating in response to failure of power to the electrical means for effecting opening operation of the master valve independently of all of the selector valves for converting the non-pressure header to a pressure header so that the delivery of the carbon dioxide to the hazards may be controlled entirely by the selector valves.

2. A fire extinguishing system for protecting a plurality of separate hazards, comprising a storage tank for supplying liquid carbon dioxide to the system, a delivery pipe extending from the tank, a master valve for controlling the flow of carbon dioxide through the delivery pipe, a header connected to the outlet of the master valve, a separate branch pipe line extending to each hazard from the header, a selector valve for controlling each branch pipe line, said master valve and selector valves being operated in response to the application thereto of differential fluid pressure, electrical means for effecting opening operation of the master valve and one selector valve for effecting delivery of the carbon dioxide to the hazard associated with the opened selector valve, and means operating in response to failure of power to the electrical means for effecting opening operation of the master valve independently of all of the selector valves for converting the non-pressure header to a pressure header so that the delivery of the carbon dioxide to the hazards may be controlled entirely by the selector valves.

3. A fire extinguishing system comprising a source of supply of liquid carbon dioxide, a piping system connecting said source of supply to a plurality of hazards and including a separate branch line for each hazard and a header common to all of the branch lines, a separate selector valve for controlling the flow of carbon dioxide through each branch line, a master valve for controlling the flow of carbon dioxide from said source of supply into the common header, electrical means for effecting opening operation of the master valve, means operating in response to any failure of electric power to the electric means for effecting opening operation of the master valve independently of all of the selector valves for converting the non-pressure header to a pressure header so that the delivery of the carbon dioxide to the hazards may be controlled entirely by the selector valves, electrical means for effecting opening operation of each one of the selector valves whenever electric power is available and regardless of whether a previous, tem-

porary failure of electric power has effected opening of the master valve, and means for manually effecting opening of the selector valves whenever electric power is not available.

4. A fire extinguishing system comprising a source of supply of liquid carbon dioxide, a piping system connecting said source of supply to a plurality of hazards and including a separate branch line for each hazard and a header common to all of the branch lines, a separate selector valve for controlling the flow of carbon dioxide through each branch line, a master valve for controlling the flow of carbon dioxide from said source of supply into the common header, electrical means for effecting opening and closing operations of the master valve, means operating in response to any failure of electric power to the electrical means for effecting opening operation of the master valve independently of all of the selector valves for converting the non-pressure header to a pressure header so that the delivery of the carbon dioxide to the hazards may be controlled entirely by the selector valves, means for manually resetting the means that operates in response to electric power failure so as to effect closing of the master valve, electric means for effecting opening and closing operations of each one of the selector valves whenever electric power is available and regardless of whether a previous, temporary failure of electric power has effected opening of the master valve, and means for manually effecting opening and closing of the selector valves whenever electric power is not available.

5. A fire extinguishing system for protecting a plurality of separate hazards, comprising a storage tank for supplying liquid carbon dioxide to the system, a header extending from the tank, a master valve for controlling the flow of carbon dioxide from the tank to the header, a separate branch pipe line extending to each hazard from the header, a selector valve for controlling the flow of carbon dioxide through each branch pipe line, said master valve and selector valves each including means for effecting its opening and closing operations in response to the proper application thereto of differential carbon dioxide pressure obtained from said tank, normally de-energized electrical means for controlling the application of said pressure to the said means of the master and selector valves to effect their opening and closing operations, and normally energized electrical means in addition to said normally de-energized electrical means for controlling the application of said pressure to only the said means of the master valve to effect its opening operation for converting the normally non-pressure header to a pressure header so that the delivery of carbon dioxide to the hazards will be controlled entirely by the selector valves.

6. A fire extinguishing system for protecting a plurality of separate hazards, comprising a storage tank for supplying liquid carbon dioxide to the system, a header extending from the tank, a master valve for controlling the flow of carbon dioxide from the tank to the header, a separate branch pipe line extending to each hazard from the header, a selector valve for controlling the flow of carbon dioxide through each branch pipe line, said master valve and selector valves each including means for effecting its opening and closing operations in response to the proper application thereto of differential carbon dioxide pressure obtained from said tank, electrical means for controlling the application of said pressure to the said means of the master and selector valves to

effect their opening and closing operations, means operating in response to power failure to the electrical means for effecting the application of said pressure to only the said means of the master valve to effect its opening operation for converting the normally non-pressure header to a pressure header so that the delivery of carbon dioxide to the hazards will be controlled entirely by the selector valves, and means in addition to the said electrical means and power failure means for controlling the application of said pressure to only the said means of the master valve to effect its opening operation to also convert the normally non-pressure header to a pressure header.

5 7. In a fire extinguishing distribution system, the combination with a source of compressed gas, a delivery pipe system therefore having a header with branches extending to different points of use, a normally-closed piston operated selector valve for each branch, each including a by-pass pilot valve to admit header pressure to the piston thereof for opening the selector valves by the effect of said pressure admission, a normally closed master valve to control the admission of gas from said source into said pipe system and a by-pass duct and pilot valve for said master valve, of electric control means including a plurality of electromagnetic pilot valve operating units, one of said units being applied to each of 20 said by-pass pilot valves, a plurality of switches respectively connected to the electromagnetic units of said selector valves, each switch controlling a circuit through one of said selector valve electromagnetic units and another circuit 25 through the electromagnetic unit of said master valve, for energizing the said two units and thereby discharging gas through a selected branch of the system, an additional by-pass duct and pilot valve for the master valve to controllably 30 admit gas pressure to the piston thereof to open the master valve and deliver gas pressure to the header so that delivery of the carbon dioxide to the said branches may be controlled entirely by the selector valves, and means operating in 35 response to the failure of power for the aforesaid electric control means for effecting opening of the said additional pilot valve and in turn the master valve.

8. A fire extinguishing system, comprising a storage tank for supplying liquid carbon dioxide, a pipe line extending from the tank for delivering carbon dioxide to the system, a valve for controlling the flow of carbon dioxide through the pipe line and being manually and automatically actuated, said valve including a body having an inlet and an outlet and a partition separating them, the partition having an opening therethrough, a cylinder, a piston movable in said cylinder in accordance with the carbon dioxide pressure therein, a valve member operatively connected to the piston and adapted to be moved thereby to control flow through the partition opening, spring means normally maintaining the piston and valve member in a position where the valve member closes the partition opening, three by-pass ducts connecting the cylinder with the carbon dioxide supply in said tank, a first automatic means, operable in response to the detection of a fire, for controlling the flow of carbon dioxide through one of said by-pass ducts to the cylinder to overcome said spring and move the valve member to open position, manual means for controlling the flow of carbon dioxide through the second of said by-pass ducts to the cylinder to likewise overcome said spring and move the

valve member to open position, and a second automatic means, operable in response to a failure of the power motivating the said first automatic means, for controlling the flow of carbon dioxide through the third of said by-pass ducts to the cylinder to likewise overcome said spring and move the valve member to open position.

9. In a system for delivering a fire extinguishing medium to a plurality of separate hazards including a separate branch pipe line extending to each hazard, and a separate selector valve for controlling each branch pipe line, the improvement which comprises an extinguishing medium delivery pipe common to all of the branch pipe lines for the hazards, a master valve in said delivery pipe for controlling the flow of the medium therethrough, normally deenergized electrical means for effecting opening operation of the master valve when energized, and normally energized electrical means for effecting opening 20 operation of the master valve when deenergized

16
as a result of failure of power to the normally deenergized electrical means.

CHARLES A. GETZ.
